UNITED STATES PATENT OFFICE

CHARLES AUTH, OF NEW YORK, N. Y., ASSIGNOR TO AUTH ELECTRICAL SPECIALTY CO. INC., OF NEW YORK, N. Y., A CORPORATION OF NEW YORK

DIRECTORY TYPE PUSH BUTTON ASSEMBLY

Application filed October 2, 1929. Serial No. 396,648.

Heretofore push buttons of the directory type have employed metal face plates overlying the whole face of the base block, and provided with recesses for the push buttons 5 and index cards, or similar constructions which usually required the use of special tools for making alterations in the index cards, and were expensive and complicated as to parts employed.

10 The present invention aims to provide a simpler and more economical assembly, wherein individual index cardholders are employed in combination with an insulating base block, with features to facilitate the insertion and removal of the index cards for alteration when desired, all as hereinafter described in greater detail. In the drawings—

20 Fig. 1 is a plan view of a push button assembly constructed in accordance with the invention, one of the index cards and its holder being removed.

25 Figs. 2 and 3 are sections taken respectively on lines 2—2 and 3—3 of Fig. 1.

Fig. 4 is a perspective view of one of the index cardholders.

30 Fig. 5 is a perspective view of a spring preferably employed in conjunction with the index cardholder.

35 In accordance with the present invention a base block 1 preferably of molded insulating material such as bakelite, is employed and provided with a row of holes 2 (Fig. 2) for receiving push buttons 3, and a recess 4 for receiving a suitable circuit making and breaking mechanism actuated by the push buttons, which mechanism is not illustrated or described herein, as suitable mechanisms for the above purpose are well known in the 40 art.

The base block 1 is provided with a plurality of depressions or recesses 5 which are respectively aligned with the holes 2 and each of such recesses receives an individual metallic index card holding frame 6, in such manner that the frame gives the appearance of being inlaid into the insulating material.

45 The recesses 5 and likewise the frames 6 are open-ended, preferably at their ends remote from the push buttons, in such manner

that the index cards 7 can be readily slipped into or out of the frames whenever desired.

50 Preferably a transparent sheet 8 of pyroxylin or similar material overlies each index card, and I also prefer to interpose a slightly bowed leaf spring 9 between each index card 7 and the bottom of its corresponding recess 5, to hold the index cards firmly in position. The bottom of each recess 5 may be provided with a notch 10 to receive the bent end 11 of the spring, to hold the latter in position while the corresponding index card is being removed.

55 The frames 6 also may be provided with ears 12 passing through holes 13 in the base block 1, and turned over as shown in Fig. 3 to lock the frames 6 in position.

60 A construction of the above nature involves the use of much less metal than has been employed heretofore in directory type push buttons, is much simpler in respect to the parts necessary to be employed, and enables the index cards to be inserted and removed with greater facility.

65 As another feature of the invention I may employ in connection with the base block 1, a bottom closure member or pad which has parts detachably holding it in position, preferably with a snap engagement. In the illustrated form of the invention this bottom closure member consists of a metal plate 14 having a soft facing 15 of rubber or the like, tongues 16 being struck inwardly from plate 14 at its opposite ends, and engageable behind shoulders 17 in spring-fingers 18 attached to the base block. Thus the closure member may be readily pried loose, whenever access is desired to the interior of the base block for changing electrical connections or other purposes, and the closure member will snap into position when forced against the base block.

70 While a specific embodiment of the invention has been described it should be understood that changes may be made therein without departing from its features as set forth in the appended claims.

I claim:

75 1. A directory type push button assembly including an insulating base block having a

100

- row of push button receiving openings therein, said block being also provided with a plurality of recesses respectively aligned with said holes, individual frames for receiving directory cards seated respectively in such recesses, said frames and recesses being open-ended.
2. A directory type push button assembly including an insulating base block having a row of push button receiving openings therein, said block being also provided with a plurality of recesses respectively aligned with said holes, individual frames for receiving directory cards seated respectively in such recesses, said frames and recesses being open-ended, and said frames having parts interlocking with the block to hold the frames in place.
3. A directory type push button assembly including an insulating base block having a row of push button receiving openings therein, said block being also provided with a plurality of recesses respectively aligned with said holes, individual frames for receiving directory cards seated respectively in such recesses, said frames and recesses being open-ended, leaf springs interposed between the frames and the base block, the base block and springs having parts engaging to hold the springs in place.
4. A directory type push button assembly including an insulating base block having a row of push button receiving openings therein, said block being also provided with a plurality of recesses respectively aligned with said holes, individual frames for receiving directory cards seated respectively in such recesses, said frames and recesses being open-ended at their end remote from the push buttons, the base block being hollow and being provided with holes extending from the bottoms of said recesses to the interior of the base block, and said frames having projections extending through said last mentioned holes and engaging with the interior of the base block to hold the frames in place.

In testimony whereof I have signed my name to this specification.

CHARLES AUTH.
